UNITED STATES PATENT OFFICE.

ROSE S. CARLING, OF LOS ANGELES, CALIFORNIA,

PNEUMATIC ARCH-SUPPORT.

1,316,423.

Specification of Letters Patent. Patented Sept. 16, 1919.

Application filed February 2, 1917. Serial No. 146,273.

To all whom it may concern:

Be it known that I, ROSE S. CARLING, a citizen of the United States, residing at Los Angeles, in the county of Los Angeles and 5 State of California, have invented new and useful Improvements in Pneumatic Arch-Supports, of which the following is a specification.

My object is to make a pneumatic arch 10 support having an inlet valve in the lower side of the air chamber and under the arch so that when the pad is inflated the foot of the wearer will not contact with the valve.

15 Figure 1 is a view in side elevation illustrating the arch support as positioned within a shoe and beneath the foot of the wearer.

Fig. 2 is an enlarged bottom plan view 20 illustrating the insole and particularly dis- 25 closing the disposition of the pneumatic pad in relation thereto.

Fig. 3 is a view in transverse section 25 through the pad, as seen on the line 3—3 of Fig. 2, illustrating the detail construction 30 of the pad and insole, bottom side up.

Referring more particularly to the drawings, 10 indicates an insole, which is here shown as formed of a flexible fabric, the under side of which has been treated with 35 rubber to prevent the insole from slipping within the shoe. This sole portion is of a shape to conform to the heel of the shoe and to extend partially under the ball of the foot. Vulcanized to the under face of the 40 insole and along the inner side of the arch is a sheet of rubberized fabric 11. This

45 fabric is secured to the insole along its marginal edge only and therefore leaves an air pocket 12. This pocket is substantially kidney shaped in plan and as shown in Fig. 3 of the drawings is substantially semi-spherical in transverse cross section.

In order to permit the pocket 12 to be supplied with air at varying pressures, an air 50 valve 13 is mounted within an opening in the center of the fabric 11. This valve is composed of a tubular stem 14 having an enlarged inner flange 15. The stem is threaded exteriorly and is engaged by a

55 locking nut 16 by which it is held in position. To more securely clamp the fabric around the stem, a clamping washer 17 is provided and interposed between the lock-nut and the fabric. The stem is formed with a central bore within which a valve member 18 is positioned, this valve being provided

to establish and discontinue communication with the pocket.

When the arch supports are used, they are placed within the shoe with the pads beneath the inner side of the foot arches. As the wearer walks, he will exert pressure upon the insole to hold it in place and at the same time will be insured that the weakened portion of the foot arch will be properly supported by means of the pneumatic pad. It will be understood that these pads have previously been inflated to a desired pressure and that they will support the foot in a comfortable manner.

Especial attention is called to the fact that the inlet valve is located at the center of the wall forming the lower side of the air chamber and under the arch of the foot of the wearer so that when the pad is inflated the air valve will not contact with the foot of the wearer.

It will thus be seen that the combined insole and arch support here disclosed is simple in its construction, will readily remain in a desired position while the wearer is walking, and will naturally and firmly support the weakened portion of the foot arches.

While I have shown the preferred construction of my arch support as now known to me, it will be understood that various changes in the combination, construction, and arrangement of parts may be made by those skilled in the art without departing from the spirit of my invention.

I claim:

1. An arch support comprising a flexible fabric insole adapted to be positioned under the heel of the foot and extend to a point beneath the ball of the foot, a sheet of rubberized material secured at its edges to the lower face of the insole and forming an air retaining pocket, and an inlet valve inserted through the center of the rubberized sheet, so as to be at the bottom of the pocket.

2. An arch support comprising a flexible fabric insole shaped to conform to the sole of the foot and to extend from a position under the heel to a point beneath the ball of the foot, a sheet of rubberized material secured to the lower face of said insole, a sheet of rubberized material forming a pocket semi-circular in shape and adapted to conform to the cavity of the arch and secured along its edges to the first-named sheet of rubberized material to form an air-

tight pocket, a second sheet of fabric covering the pocket thus formed and the insole, and an air valve positioned through this sheet of fabric at its center and through the 5 wall of the pocket, so as to be at the bottom of the air chamber.

3. An arch support comprising a flexible insole, a sheet of material secured to the

bottom of the insole and forming an air chamber, and an air valve mounted in the 10 lower sheet of material so as to be at the bottom of the air chamber when the chamber is inflated.

In testimony whereof I have signed my name to this specification.

ROSE S. CARLING.
